UNITED STATES PATENT OFFICE.

GEORGE T. PEARSONS, OF NEW YORK, N. Y.

FIRE EXTINGUISHER.

Application filed June 28, 1920. Serial No. 392,224.

This invention relates to fire extinguishers in which a fire extinguishing liquid in a container is expelled by placing the liquid under a fluid expelling pressure when the liquid is to be discharged from the container, and it is the main object of the invention to provide an improved chemical gas generator to create or generate gas by the uniting or mixing of gas generating materials in the generator to constitute the expelling pressure for the liquid and to provide outlet means for the generated gas leading into the container from the generating chamber at a point remote from that portion of the chamber in which the united gas generating materials are reacting in all positions of the generator to prevent the entrainment of the gas generating materials with the generated gas from the generator into the container.

It is a further object of the invention to provide a gas generator for this purpose in which the gas generating materials are maintained in a separated condition in the normal upright position of the generator and adapted to unite when the generator is inverted, and having outlet means with the outlet leading into the container above the level of the liquid in the container in the normal position of the extinguisher, and the inlet to said outlet means being located at a point substantially centrally of the generator chamber. It is another object of the invention to provide a carrier or holder for the generator to suspend the same in the container, said carrier having an outlet port or ports for the generated gas opening into the container above the level of the liquid therein in the normal position of the extinguisher.

A still further object of the invention relates to a chemical gas generator including a gas generating chamber and a receptacle carrying an acid, such as hydrochloric or sulphuric acid, constituting one of the gas generating materials in said chamber, with means through which the generated gas is discharged arranged to carry another gas generating material in the form of a dry substance, such as bicarbonate of soda, and maintain the same in a separated condition from the acid in the receptacle in the normal position of the generator, and said means also arranged to place the

acid receptacle into and remove it from the generating chamber, as well as position said receptacle at one end of the generating chamber in all positions thereof. 55

Other objects and advantages will herein-after appear.

In the drawings accompanying and forming a part of this specification I have shown an embodiment of my invention applied to a 60 fire extinguisher in which Fig. 1 is a sectional side elevation.

Fig. 2 is a sectional side elevation of the chemical gas generator showing a modification of the outlet means for the generator and 65 a holder or carrier for suspending the generator in the container for the fire extinguishing liquid of the extinguisher.

Fig. 3 is a view similar to Fig. 1 showing a 70 modification of the chemical gas generator; and Figs. 4 and 5 are sectional side elevations showing modified forms of the chemical gas generator shown in Fig. 1.

Similar characters of reference designate like parts throughout the different views of 75 the drawings.

In Fig. 1 of the drawings I have shown an embodiment of my invention in connection with a fire extinguisher comprising a reservoir or container 6 for the fire extinguishing liquid 80 having a discharge outlet 7 and an opening in a head 8 at the top having a removable closure 9.

To create or generate a fluid pressure in the container to expel the fire extinguishing liquid 85 from the discharge outlet a chemical gas generator is provided comprising a chamber or receptacle 10 open at one end and having a removable closure 11 therefor. This receptacle is suspended in the container 6 by the 90 closure thereof engaging an inwardly extending flange 12 of the head 8 and positioned on said flange by lugs 13 on the closure 11 engaging or lying contiguous to the closure 9 for the opening in the head 8. 95

A receptacle, such as a bottle 15, carrying an acid as hydrochloric or sulphuric acid, and constituting one of the gas generating materials, is seated in a tubular member 14 mounted in the chamber 10, said member being of 100 less sectional area than the chamber to provide a space between the walls of said mem-

ber and the chamber and the member 14 arranged to maintain it in spaced relation to the wall of the chamber. The receptacle 15 has a perforated stopper 16 to maintain the acid receptacle open to the member 14 and generating chamber 10. A dry substance 17, such as bicarbonate of soda, and constituting the other gas generating material is carried in the member 14 in superposed relation to the acid receptacle and maintained in separated condition from the acid in the receptacle 15 by a supporting disk or plate 18, said disk being in spaced relation to the stopper. The acid receptacle is positioned at one end of the generating chamber by a rod 19 fixed in the stopper and extends to adjacent the cover 11 and on which rod the disk is slidably mounted. The member 14 may be provided with a hooked rod 20 to facilitate the placing of the member 14 and the acid receptacle and dry substance into the generating chamber and the removal of the same. The gas generating materials are maintained in separated condition in the normal upright position of the generator and adapted to unite and react when the generator is inverted. It will be obvious that as the generator is inverted that the acid will flow through the stopper perforations onto the plate 18 and flow from said plate to the bicarbonate of soda, the initial reaction of the mixing of the acid and soda serving to dislodge the soda from the member 18 to the top which is then the bottom of the generator.

The generated gas is discharged from the generating chamber through an outlet tube 21 having an outlet at one end of the generating chamber, and as shown in Fig. 1 located in the closure 11, as at 22, above the liquid level in the container 6 in the normal position thereof with the inlet to the outlet tube substantially centrally of the generating chamber, whereby said inlet is at a substantial distance from the seat of reaction of the generating materials both when the generator is inverted and when it is righted after use. In the structure shown in Fig. 1 the generated gas enters the space in the head 8 between the closure 9 and generator and to permit the entrance of the gas therefrom to the container 6 the flanged portion 12 of the head is provided with perforations 23. During the initial uniting of the gas generating materials there is a sudden and violent reaction and consequent scattering of the materials as well as a violent frothing of the reacting materials and by the extending of the discharge tube into the generator chamber as set forth the discharge or entrainment of a portion of the gas generating materials with the discharge of the gas is prevented. Furthermore should the extinguisher again be moved to upright position with the consequent falling of the soda to the bottom of the generator, then lowermost, and on to the acid there will again be a sudden and

violent reaction but such discharge tube extending only to substantially centrally of the generator chamber the entrainment of the gas generating materials with the discharge of the gas is obviated.

The structure of the gas generator shown in Fig. 2 is similar to that shown in Fig. 1 with the exception that the generating chamber is arranged with the opening and the closure 11 having the outlet therein lowermost in the normal position of the generator the generator being suspended in the container or reservoir 6 by means of an open end holder or carrier 24, the generator being maintained in spaced relation to the holder by a lug 25 projecting up from the bottom of the holder or it may be arranged on the closure for the generator. The holder has a flange 26 at the open end adapted to engage the head flange 12 of the container to suspend the holder with the generator in the container, the discharge of the generated gas being from the generator into the holder and from the latter into the container through ports 27 adjacent the open end and above the liquid level in the container in the normal position thereof. The operation of the generator as shown in Figure 2 is the same in all respects as the operation of the generator shown in Figure 1.

In the structure shown in Figure 3 the acid receptacle is carried in the generating chamber in a holder 28 having a hooked rod 29 secured thereto extending to adjacent the open end of the generating chamber to permit placing of the acid receptacle into and removing the same from the chamber 10. The discharge of the generated gas is through a tube 30 extending into the chamber 10 from the closure thereof to adjacent the acid receptacle and having a disk portion 31 to perform the function of the disk 18 in the structure shown in Figure 1, and to engage and position the acid receptacle at one end of the generating chamber, the disk portion 31 being in spaced relation to the receptacle stopper to permit of the ready flow of the acid from the receptacle through the stopper perforations. The disk 31 serves when the extinguisher is inverted to deflect the gas generating liquid away from the tube 30 and the opening 35 therein. The bicarbonate of soda is contained within a foraminous carrier 32 mounted on the discharge tube 30 maintained adjacent the closure 11 of the generating chamber by a flanged disc 33 releasably connected to the tube by screw threading as at 34. By unscrewing said disc it may be adjusted along the tube and permit refilling of the carrier with bicarbonate of soda. The inlet to the discharge tube for the generated gas from the generating chamber is through a port or ports 35 located substantially centrally of the generating chamber for the same purpose as extending the discharge tube

21 in the structure shown in Figure 1, into the generating chamber with the inlet substantially centrally thereof. As the generator is set in operation by inverting the same 5 the acid from the receptacle 15 will be discharged onto the disc 33 and will flow from the latter to the top, which is then the bottom of the generating chamber, where it will unite with the soda. The disc 33 also serves 10 as a baffle for the generated gas to further insure the prevention of the entrainment of the gas generating materials with the discharged gas.

The modification shown in Fig. 4 is similar 15 to that shown in Figure 3 with the exception that the carrier 28 for the acid receptacle is omitted and the discharge tube is arranged with a band carrying spider 36 having bayonet slots therein to cooperate with pins 38 20 projecting from a band 39 about the neck of the acid receptacle to place the receptacle into and remove it from the generating chamber and which may be simultaneous with the applying and removing of the closure from the 25 generating chamber. The bicarbonate of soda is carried in a holder 40 having a perforated bottom slidably mounted on the outlet tube and in the normal upright position of the generator supported upon a disk 41 30 fixed to the outlet tube. The holder also has projections 42 to engage the top of the generator when inverted to provide an open space between the holder and end of the generator to permit of the access of the acid to 35 and uniting of the same with the soda. The disk 41 also serves as a baffle to prevent entrainment of gas generating material with the discharge of the generated gas.

In the structure shown in Figure 5 the soda 40 in the normal position of the generator is carried by a disk 43 in a manner similar to that shown in Figures 1 and 2 with the exception that the member 14 is omitted, and the disk has a bayonet joint connection, with the acid receptacle similar to that shown in Figure 4. The disk 43 is carried by the outlet tube 30' to place said disk and acid receptacle into the generating chamber and removing the latter from such chamber by the placing and 45 removing of the closure 11 from the generating chamber.

The outlet tube 30 has an outlet port or 50 ports 45 adjacent its connection with the closure 11 and an outlet port or ports 46 substantially centrally of the generating chamber. A sleeve 47 of less length than the outlet tube is slidably mounted on the latter to have movement between the closure 11 and an abutment 48 at the end of the tube within 55 the chamber, and is operable to shut off the port or ports 45 from the chamber when the port or ports 46 are open thereto and vice versa. When the generator is inverted to set the same in operation the sleeve will cover 60 the ports 45 and the discharge of the gen-

erated gas will be through ports 46, and should the generator again be moved to upright position the sleeve will cover the ports 46 and open the ports 45. By this arrangement the inlet of the discharge tube of the 70 generating chamber is at all times remote from that portion of the generating chamber in which reaction of the gas generating materials is taking place.

It will be noted that in all of the structures that while the acid in the acid receptacle is at all times open to the generating chamber and soda the gas generating materials are maintained in a separated condition, and that the outlet for the generated gas is above the liquid level in the normal upright position of the extinguisher. The fire extinguishing liquid used is carbon tetrachloride which is of a highly evaporable nature when open to the air and to provide an open and unobstructed 80 passage for the discharge outlet of the container 6 and at the same time seal the liquid in the container from the air, a liquid seal is provided for the outlet. For this purpose a chamber 47' is connected to the outlet 7 of the container, said chamber having an outlet 48' to which a hose or discharge nozzle 49 may be connected, a tube 50 being secured in said outlet to extend into the chamber and constitute 85 a continuation of the outlet. The chamber is open at the upper end and has a removable closure 51. The portion of the chamber having the outlet extends somewhat below the connection of the chamber with the container outlet 7 and is filled with a liquid which is 90 non-volatile and non-miscible with the fire extinguishing liquid, shown at 52, glycerine having been found to answer this purpose.

A tubular casing 53 integral with or secured to the closure extends over the tube 50 and 100 into the liquid 52 thereby forming a trap or pocket and sealing the outlets of the chamber and container from the atmosphere. In operation as the liquid in the container 6 is discharged under the force of the fluid expelling pressure the liquid will be discharged 105 into the chamber 47' passing up into the casing 53 and from said casing through the outlet tube 50 and connected hose 49.

By the arrangement of the connection of 110 the closure 9 with the head 8 for the opening therein, and the manner of supporting the generator from the head a space is provided between the top of the generator and the closure 9 when the extinguisher is inverted 115 by the engagement of the projections 13 of the generator closure with the closure 9 permitting of the entrance of fire extinguishing liquid and which will serve to seal the connection of the closure 9 with the head preventing the escape of the generated fluid expelling pressure through said connection. In the use of the holder 24 for the generator shown 120 in Figure 2 and the arrangement of the discharge orifices 27 in superposed relation as 125

shown and spaced from the open end of the holder as the extinguisher is inverted, a space is provided between the end of said holder and the ports therein and the closure 9 to 5 pocket a portion of the fire extinguishing liquid to seal the connection of the closure 9 with the head 8, the arrangement of the ori-fices 27 permitting entrance of the liquid to such pocket and the escape of the generated 10 gas into the container 6.

Having thus described my invention I claim:

1. In a fire extinguisher, a liquid container having an outlet above the normal liquid level, an opening in said container having a removable cover, a gas generator supported within the liquid container in substantially axial alignment with said opening, said generator having an outlet which opens therefrom to the exterior thereof at a point located above the normal liquid level of said container in the normal position thereof, gas generating materials in said generator held in a separated condition in the normal inoperative position of the extinguisher and operable to unite when the container is inverted to create a gas and place the liquid in the container under fluid pressure to eject the liquid from said container.
2. The combination with a liquid carrying container having an opening in the top with a removable closure, a gas generator in the container to place the liquid therein under fluid expelling pressure comprising a receptacle having an outlet leading from a point substantially centrally of the receptacle, means in said receptacle to maintain gas generating materials in a separated condition in the normal upright position thereof and adapted to unite when inverted, and means to suspend the generator from the opening in the container with the outlet for the discharge of the generated gas into the container above the liquid level therein in the normal position of the container.
3. In a generator for fluid pressure, a chamber, a receptacle for gas generating material in said chamber, means to carry another gas generating material in superposed relation to the receptacle arranged to position the receptacle at one end of the chamber, and an outlet tube leading from one end into the chamber and having an inlet substantially midway of the chamber.
4. In a generator for fluid pressure, a chamber having an open end with a removable closure; a receptacle for a gas generating material; means to place said receptacle into and remove it from the chamber and positioned at one end of the receptacle; means to carry another gas generating material in superposed relation to the receptacle in the upright position of the chamber and to permit the material in the receptacle to unite therewith when the receptacle is in-

verted; and an outlet tube leading into the chamber from one end thereof and having an inlet substantially midway of the chamber.

5. In a generator for fluid pressure, a chamber; a receptacle in said chamber for a gas generating material; an outlet tube leading into the chamber from one end and having an inlet substantially centrally of the chamber; and means on said tube to carry another gas generating material above the inlet to the tube and in superposed relation to the receptacle in the normal position of the generator and with which material the material in the receptacle is adapted to unite when the generator is inverted, and said means adapted to serve as a baffle for the reacting materials when uniting in all positions of the generator.

6. In a generator for fluid pressure, a chamber; a receptacle in said chamber for a gas generating material at all times open to the chamber; an outlet tube leading into the chamber from one end and having an inlet substantially centrally of the chamber, said tube being arranged to position the receptacle at one end of the chamber; and means on said tube to carry another gas generating material above the inlet to the tube superposed to the receptacle and in separated condition from the material in the receptacle.

7. In a generator for fluid pressure, a chamber having an open end with a removable closure; an acid carrying receptacle in said chamber; an outlet tube extending from the closure into the chamber having an inlet substantially centrally of the chamber and arranged to position the receptacle at one end of the chamber in all positions of the generator; cooperating means arranged on the tube and receptacle to connect the receptacle to the tube to place the receptacle and remove same from the chamber; means mounted on the tube to carry a dry substance above the inlet to the tube in superposed relation to the acid receptacle and maintain said substance in separated condition from the acid in the receptacle and permit the acid to unite therewith when the generator is inverted, said means also serving as a baffle for the reacting material in all positions of the generator.

8. In a fire extinguisher, a liquid container having an outlet above the normal liquid level, an opening in said container having a removable cover, a gas generator removably supported in substantially axial alignment with said opening, gas generating materials in said generator normally held in a separated condition and operable to unite when the container is inverted to create a gas pressure to eject the liquid from said container, and a gas passage connecting the interior of the gas generator with the exterior thereof at a point above the level of the liquid in said container in the normal inoperative position of the extinguisher.

9. In a fire extinguisher, a liquid container having an outlet above the normal liquid level, an opening in said container having a removable cover, a gas generator supported in substantially axial alignment with said opening, gas generating materials in said generator normally held in a separated condition and operable to unite when the container is inverted to create a gas pressure to eject the liquid from said container, and an open passage from the interior of the generator to the exterior thereof having an opening therefrom above the liquid level in said container in the normal inoperative position of the extinguisher, and an inlet within the generator located at a distance from the reacting gas generating materials when said container is inverted.
10. In a fire extinguisher, a liquid container having an outlet above the normal liquid level, an opening in said container having a removable cover, a gas generator supported in substantially axial alignment with said opening, gas generating materials in said generator normally held in a separated condition and operable to unite when the container is inverted to create a gas pressure to eject the liquid from said container, and a passage connecting the generator to the container in open communication with said container having an opening to the exterior of the generator located at a point above the liquid level in said container in the normal inoperative position of the extinguisher, and an inlet orifice within the generator located at a distance from the reacting gas generating materials when said container is inverted, and when said container is returned to its normal position after having been inverted.
11. In a fire extinguisher, a container for a liquid having an outlet therefrom above the normal liquid level, an opening in said container having a removable cover, a gas generator removably supported in substantially axial alignment with said opening to carry chemical means normally in a separated condition and operable when the container is inverted to unite and create pressure to eject the liquid from said container, and a passage connecting the interior of the generator to the exterior thereof at a point free from contact with the liquid in the container in the normal position of the container.
12. In a fire extinguisher, a container for a liquid having an outlet above the normal liquid level therein, an opening in said container having a removable cover, a gas generator having a removable cover and supported adjacent said opening carrying chemical means normally held in a separated condition and operable when the container is inverted to unite to create pressure to expel the liquid from said container, a passage for taking the gas from the generator to the container when the extinguisher is inverted, said passage leading from the generator at a point removed from the said reaction of the reacting chemicals when the extinguisher is inverted and leading to the container at a point removed from contact with the liquid when the extinguisher is in normal position.
13. In a fire extinguisher, a container for a liquid having an outlet above the normal liquid level therein and an opening with removable cover, a gas generator removably supported in substantially axial alignment with said opening and having a removable cover and arranged with a passage extending from within the generator to within the container, the connection with the container being removed from contact of the liquid in said container in normal position thereof, chemical means in said generator normally held in a separated condition and operable to unite to create pressure when the container is inverted to eject the liquid from said container.
14. In a fire extinguisher, a container for liquid having an outlet, an opening in said container with removable cover, a gas generator pendently supported in said opening, gas generating materials in said generator normally held in a separated condition and operable when the container is inverted to unite to create a pressure to expel the liquid from said container, a passage from said generator opening therefrom above the normal liquid level in the container, said passage connecting with the interior of the generator at a point distant from the position taken by the reacting gas generating materials when the container has been inverted and returned to normal position after inversion.
15. In a fire extinguisher, a liquid carrying container having an outlet therefrom above the normal liquid level therein and an opening with a removable cover, a gas generator in said container carrying chemical means in a separated condition to create a pressure when the container is inverted to eject the liquid from said container, and having open communication with a portion of the liquid carrying container above the gas generator in the normal position of the container.
16. In a fire extinguisher a liquid container for fire extinguishing liquid, a gas generator supported within the liquid container said generator having an outlet passage opening into the container above the liquid level therein in the normal position of the container, the inlet of said passage within the generator being so positioned as to be above the seat of reaction of the gas generating materials in said generator in all positions of the extinguisher.
17. In a fire extinguisher a liquid container for fire extinguishing liquid, a gas generator supported within the liquid container, a container for a gas generating liquid and a container for a gas generating material in said container, an outlet passage leading from said

gas generating chamber to the exterior thereof above the normal liquid level in said first mentioned liquid container and means for deflecting the gas generating liquid away from the inlet to said passage when the extinguisher is inverted.

18. In a fire extinguisher in combination, a tank for fire extinguishing liquid, a gas generator supported within said tank comprising a closed container, gas generating materials supported within said container and arranged to unite when the generator is inverted, said container having an opening located above the fire extinguishing liquid in the normal upright position of the extinguisher, which opening opens from said generator at the top whereby the fire extinguishing liquid cannot pass into the gas generator through said opening.
19. In a fire extinguisher in combination a tank for fire extinguishing liquid, a gas generator supported within said tank comprising a casing, gas generating materials within said casing arranged to unite when the generator is inverted and a tube for conveying gases out of said casing which tube opens into the casing toward the central portion thereof and has its outlet to the exterior of the casing at a point above the normal liquid level of the fire extinguisher liquid when the tank is in upright normal position and so arranged that the gas generating material will not pass out of the casing through said outlet tube.
20. In a fire fighting device, a tank for a fire extinguishing liquid having an opening, a gas generator in said tank supported adjacent the top thereof comprising a tubular casing having an opening at its top end in the normal upright position thereof and a closure therefor, an outlet opening in said generator adjacent the top, gas generating materials in said casing arranged to unite to create pressure when the generator is inverted, a tubular member in said casing in communication with the outlet opening of said generator operable and so arranged as to exclude the fire extinguishing liquid from the generator in the normal upright position of the tank and when the tank is inverted to afford a gas passage from the generator and provide means to prevent entrainment of the gas generating materials.
21. A gas generator comprising a tubular casing, having a rigidly sealed bottom at one end and an opening and a closure therefor at the other end, said generator having an outlet adjacent the top end thereof, a receptacle having a stopper in said generator to carry a gas generating material, another gas generating material in said generator, the gas generating materials being so arranged as to unite to create pressure when the tank is inverted, means in said generator arranged to govern the movements of the stopper and the receptacle when the extinguisher is inverted and tubular means in communication with said outlet to

prevent the entrainment of the gas generating materials in the outgoing gas when the generator is inverted.

22. In a fire fighting device, a tank for fire extinguishing liquid having an opening and a closure therefor and a discharge outlet, said opening being above the normal liquid level of the tank in its normal upright position thereof, a gas generator in said tank having an outlet therefrom, a gas generating material in said generator, a receptacle for another gas generating material, said gas generating materials being held in a separated condition and arranged to unite to create pressure when said tank is inverted, a tubular member in said generator in communication with the generator outlet with its inlet from the generator above one of the gas generating materials in the normal upright position of the tank and so arranged as to convey the generated gas from said generator when inverted.

23. In a fire fighting device, a container for fire extinguishing liquid having an opening and a closure therefor above the liquid level therein in the normal upright position thereof and a discharge outlet therefor above the normal liquid level in the upright position of the container, a chemical gas generator in said container having an outlet to the exterior thereof intact from the container liquid and above the normal liquid level thereof in the upright position of said container, a chamber in said generator adjacent one end thereof to hold a gas generating material, a receptacle in said generator to hold another gas generating material, said gas generating materials being arranged to create a pressure when the container is inverted, a chamber at the other end of the generator adapted to receive the gas generating materials when the extinguisher is inverted and tubular means having an inlet in communication with said generator outlet and positioned to prevent the gas generating materials being ejected to the exterior of the generator when the container is inverted.

24. In a fire fighting device, a container for fire extinguishing liquid having an outlet and an opening with a closure therefor, said outlet being above the normal liquid level in said container in the normal upright position thereof, a gas generator in said container having an opening therefrom at a point above the normal liquid level in the container in the normal upright position thereof, gas generating materials in said generator so arranged as to create a gas pressure when the container is inverted, and means in the line of the gas passage between the seat of the reaction of the gas generating materials and the interior of said container operable to stagger the gas and prevent the entrainment of the gas generating materials with the generated gas when the container is inverted.

25. In a gas generator a container for gas

generating materials having an opening with a removable cover, gas generating materials in said container including a gas generating liquid said gas generating materials being normally held in separated relation, a tubular member for conducting the generated gas from said container to the outlet opening to the exterior thereof adjacent to the top or cover end, said tubular member opening into the container substantially centrally thereof whereby the opening of said outlet will be above the level of liquid in the container to prevent escape of liquid through said tubular member in either upright or inverted position of the container.

26. In a fire extinguisher, a tank for a fire extinguishing liquid having an opening and a closure therefor above the normal liquid level therein in its upright position, a chemical gas generator in said tank having an outlet therefrom above the liquid level therein in the normal upright position thereof, generating materials in said tank held in a separated condition and operable to unite when the tank is inverted to create a pressure to eject the liquid from said tank and means in said tank to retard the entrainment of the gas generating materials with the generated gas.

30. 27. In a fire extinguisher, in combination, a tank for a fire extinguishing liquid having an opening and a cover therefor, and a discharge outlet, a gas generator in said tank comprising a casing, a gas generating material in said generator, a tubular member within said generator arranged to conduct generated gas from the generator to the tank, a receptacle for another gas generating material maintained in predetermined position by said tubular member, said tubular member having an inlet from the gas generator above the level of one of the gas generating materials when the container is in normal upright position, the gas generating materials being arranged to unite when the generator is inverted.

28. A chemical gas generator comprising a chamber, chemical gas generating means maintained in said chamber in a separated condition and arranged to unite to create gas when the generator is inverted, a tube opening into said generator at a distance from the top thereof and opening therefrom through the top of the generator in its nor-

mal upright position and arranged to convey the generated gas therefrom and exclude the gas generating materials from the exterior thereof when the generator is inverted.

29. In a fire fighting device, a tank for a fire extinguishing liquid having an opening, a gas generator in said tank having an opening and supported adjacent to the top thereof, said generator having a closure for the opening and an outlet at the top end thereof, a gas generating material in said generator, a receptacle in said generator to contain another gas generating material, a tube in said generator connected to the outlet having an inlet thereto positioned intermediate the gas generating materials in the normal upright position of the tank and above both gas generating materials when the extinguisher tank has been inverted.

30. In a fire extinguisher, a container for a fire extinguishing liquid having an outlet, a chemical gas generator in said container to contain gas generating materials held in separated condition and operable to unite to create pressure when the container is inverted, said generator having an outlet to connect the interior of the generator with the exterior thereof above the liquid level in the container, tubular means connected with said outlet to conduct the generated gas to the exterior thereof, and means to shut off communication between the interior of the generator and the exterior of the container when the container is in its normal upright position.

31. In a fire extinguisher a container for a fire extinguishing liquid, a chemical gas generator in said container to contain gas generating materials held in a separated condition said gas generator having a passage opening into said container at a point removed from the seat of reaction of the gas generating materials when the container is inverted and passing toward the top of said generator to a point above the level of the liquid in the container when the extinguisher is in upright position, said passage opening into said container.

Signed at the city of New York in the county of and State of New York this 10th day of June, 1920.

GEO. T. PEARSONS.
